UNITED STATES PATENT OFFICE.

ELLIS N. WEBB, OF GENEVA, NEW YORK.

PRESSER FOOT.

Application filed February 16, 1922. Serial No. 537,138.

To all whom it may concern:

Be it known that I, ELLIS N. WEBB, a citizen of the United States, residing at Geneva, in the county of Ontario and State of New York, have invented a new and useful Presser Foot, of which the following is a specification.

This invention relates to a presser foot designed primarily for use on out sole stitching machines such as used by shoe repairmen.

One of the objects of the invention is to provide a presser foot which will hold the knife adjustably whereby it is possible to keep the point of the knife in perfect alignment with the awl and the needle.

Another object is to provide means whereby the knife can be adjusted laterally so as to compensate for any differences in the positioning of the point of the awl due to the particular way in which the awl is sharpened.

Another object is to provide a presser foot which will hold the point of the knife closer to the awl than has heretofore been possible and which will hold the knife firmly while in operation.

A further object is to provide a presser foot which prolongs the life of the knife because it is possible for the operator to keep the original bevel on the cutting point and thus make a perfect groove at all times and with the minimum wear on the cutting tool.

Another object is to provide a structure of this character which can be reached readily at all times for the purpose of making adjustments or for disconnecting the parts.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a front elevation of the presser foot and the knife engaged thereby.

Figure 2 is a side elevation of the structure shown in Figure 1.

Figure 3 is a plan view.

Figure 4 is a bottom view.

Figure 5 is a front elevation of the presser foot and the clamp combined therewith.

Figure 6 is an elevation of the inner side 60 of the presser foot and clamp.

Referring to the figures by characters of reference 1 designates the holding block of the presser foot, the same being provided with screws 2 or the like for attaching it to 65 a machine. This holding block has spaced ears 3 extending from the outer end thereof and designed to receive between them an ear 4 projecting upwardly from the presser foot 5. A dowel 6 is extended laterally 70 from the presser foot and is adapted to enter an opening 7 formed within the block 1. Projecting rearwardly from the presser foot is an ear 8 and a similar ear 9 is extended rearwardly from the block 1. The 75 base 10 of the presser foot is adapted to ride under the block 1 and for the purpose of shifting the presser foot relative to the block an adjusting screw 11 is provided. This screw is swiveled within the ear 9, there 80 being an annular groove 12 in the screw for the reception of a retaining pin 13. The threaded portion of the screw engages the ear 8. A kerf 14 is formed in the free end of the screw so that by inserting a screw 85 driver thereinto the screw can be rotated and will thus shift the presser foot toward or from the block 1 and correspondingly move the ear 4 between the ears 3. The opening in ear 8 for the reception of the screw 11 90 has been shown at 15 in Figure 6. For the purpose of holding the screw 11 against rotation a set screw 16 is extended into the ear 9 so as to engage screw 11. Thus accidental shifting of the parts subsequent to 95 adjustment can be prevented.

An inclined angular groove 17 is formed in the outer side of the presser foot 5 and registers with a similar groove 18 formed in the inner side of a clamp 19. This clamp 100 is adapted to engage the outer face of the presser foot 5 and has an ear 20 movable between the ears 3. A knife 21, angular in cross section, is adapted to be received by the two grooves 17 and 18. The lower portion of the knife has its sides and end beveled as at 22 so as to provide a cutting edge 23 and a cutting point 24. The thickness of the angular portion of the knife 21 is slightly greater than the combined depths of the two grooves 17 and 18. Thus by means 105 of a clamping screw 25 extending through

the clamp 19 and engaging the presser foot 5, the knife 21 can be held tightly between the presser foot 5 and the clamp 19. This clamping of the knife is effected after the 5 knife has been adjusted longitudinally to project its point a desired distance below the base 10. As soon as this adjustment has been effected the presser foot can be adjusted laterally relative to the block 1 so as to 10 bring the point of the knife into proper alignment with the awl and needle.

What is claimed is:—

1. The combination with a holding block, of a presser foot having a base movable 15 under the block, spaced ears extending from the block, an ear on the presser foot slidable between the ears, screw threaded means for minutely adjusting the presser foot laterally toward or from the block, a clamp, 20 there being inclined angular grooves in the meeting faces of the presser foot and clamp, said grooves registering, an elongated knife angular in cross section seated in the registered grooves, screw threaded means for adjusting the clamp relative to the presser foot, 25 to grip the knife, said knife having a beveled end terminating in a cutting point.
2. The combination with a holding block having spaced ears extending from the upper 30 portion thereof and a laterally extending ear, of a presser foot slidable under the spaced ears and having a laterally projecting base slidable under the holding block, an upstanding ear upon the presser foot and 35 slidable between the spaced ears, a clamping block, a laterally extending ear upon the presser foot, an adjusting screw connecting said ear to the laterally extending ear on the block for minutely adjusting the presser 40 foot laterally relative to the block, said presser foot and clamp having matching inclined grooves in their meeting faces, an elongated knife angular in cross section seated within the groove and having beveled 45 faces at one end terminating in a cutting point, and an adjusting screw engaging the

clamp and presser foot for binding them upon the knife, said knife being held by friction in the groove.

3. The combination with a presser foot 50 having a base, and means for minutely adjusting the presser foot laterally, of a clamp, said clamp and presser foot having matching inclined angular grooves, an elongated 55 knife angular in cross section seated in the groove and projecting upwardly and downwardly beyond the grooves, the lower end of the knife having its sides and end beveled to provide a cutting point and a cutting edge, means for minutely adjusting the 60 clamp relative to the presser foot for binding them upon the knife.

4. The combination with a holding block for fixed attachment to a stitching machine, of a presser foot having a base slidable 65 under the holding block, cooperating means upon the block and presser foot for holding said presser foot against tilting movement relative to the holding block, an adjusting screw engaging the presser foot and 70 holding block for minutely adjusting said presser foot laterally relative to the block, a clamp, said clamp and presser foot having matching inclined grooves in their meeting 75 faces, an elongated knife angular in cross section and seated in the grooves, one end of the knife having its side and end beveled providing a cutting point and a cutting edge adapted to be positioned close to the awl of a stitching machine, and an adjusting screw 80 engaging the presser foot and clamp for gripping the knife between said presser foot and clamp to hold it against longitudinal displacement.

In testimony that I claim the foregoing 85 as my own, I have hereto affixed my signature in the presence of two witnesses.

ELLIS WEBB.
